CLAIM

The ornamental design for a carry strap, as shown and described.

DESCRIPTION

FIG. 1 is a perspective view of a carry strap showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and

FIG. 8 is a perspective view thereof shown in a second state for clarity of disclosure;

FIG. 9 is a perspective view thereof in used with an unclaimed tent; and,

FIG. 10 is a perspective view thereof in used with an unclaimed tent and a man.

The broken lines in the drawings depict portions of the carry strap that form no part of the claimed design.
